UNITED STATES PATENT OFFICE.

HOWARD TERHUNE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

BOARD DROP-HAMMER.

1,246,182.

Specification of Letters Patent. Patented Nov. 13, 1917.

Application filed June 26, 1916. Serial No. 105,868.

To all whom it may concern:

Be it known that I, HOWARD TERHUNE, a citizen of the United States, and a resident of Chambersburg, in the county of Franklin and State of Pennsylvania, have invented certain new and useful Improvements in Board Drop-Hammers, of which the following is a specification.

My invention relates to improvements in board drop hammers and more particularly to improvements in means for carrying the clamps which engage and hold the board which carries the ram after the latter has been lifted to its raised position, the object of my invention being to furnish certain improvements in the "floating head" type of hammer which will prevent the flying of parts and the possible injury of the operator in case of breakage of said head.

In the accompanying drawings forming part of this specification and in which similar letters of reference indicate similar parts throughout the several views:—

Figure 1, is a side elevation, partly in section, of the upper end of a board drop hammer embodying my invention:

Fig. 2, a plan of the board clamp plate, the clamps, and the arms by means of which the shafts carrying the clamps are operated:

Fig. 3, a plan of board clamp plate:

Fig. 4, a section of Fig. 3 on line A—A:

Fig. 5, a side elevation of a board clamp:

Fig. 6, a side elevation of eccentric shaft upon which board clamps are carried:

Fig. 7, an end elevation of Fig. 6:

Fig. 8, a plan of head piece, bolted to top of the side frames of the hammer, which carries the plate carrying the board clamps, the elevating rolls, etc.:

Fig. 9, a side elevation of Fig. 8.

To the top of the side frames 2 of the hammer is bolted the head piece 3 the bottom of which carries lugs 14 cast integral with it. The floating plate 12, which carries the board clamps 10—11, is carried upon the top of the head piece 3 its bottom plate being perforated to receive the lugs 14 which are a loose fit in said perforations so that said head may have some play.

In the sides of the floating head 12 are journaled the eccentric shafts 4, Figs. 6 and 7, which carry the board clamps 10—11 and which, themselves, carry the crank

arms 17—19, Fig. 2, which are operated in a well-known manner to bring the board clamps 10—11 into or out of operative contact with the board 5, Fig. 2.

In the drawings the floating plate with its board clamps is shown beneath the rolls which elevate the board and ram. By proper modifications, which will occur to any mechanic, the floating plate may be placed above the board operating rolls. Likewise it will be seen that the positions of the lugs 14 and of the slots 6 may be reversed, that is that the lugs may be carried by the floating plate 12 and the slots be formed in the stationary head piece 3.

All the strains due to the movements of the board clamps are transferred to the floating plate and as this plate is weakest in the middle it will break at this point if overstrained. In course of time this is very apt to happen but if it does the lug and slot arrangement will prevent any of the broken parts from leaving the machine and doing damage to persons or property in its vicinity.

Another advantage of mounting the board clamps in a floating plate is that this arrangement permits these clamps to follow the irregularities of the board while they are at all times still under perfect control of the operator.

As this application is confined to the floating plate arrangement for carrying the board clamps, I have not deemed it necessary to describe the other parts of the hammer all of which are well known. I may say, however, that I am aware that floating plates have before been used in connection with drop hammers but to the best of my knowledge they have not before been provided with means, other than the board, for limiting their travel and no provision has been made in connection with them for preventing a broken part or parts from injuring those who may be about the hammer when the plate breaks.

Having thus described my invention I claim as new and desire to secure by Letters Patent:—

1. The combination with the board clamps of a drop hammer, of a floating plate carrying said clamps and a head piece carrying said floating plate, the head piece and plate having lugs and slots and adapted to

engage one another substantially as and for the purposes set forth.

2. The combination with the board clamps of a drop hammer, of a head piece thereon, **5** a floating plate carrying said clamps and weakest at the middle, and separate coöperating engaging means between the head piece and the two parts of the floating plate on opposite sides of the middle adapted to **10** retain each of these parts in case of breakage.

3. The combination with the board clamps of a drop hammer, of a head piece thereon and a floating plate interfitting with the

head piece to prevent excessive lateral move- **15** ment of one with respect to the other.

4. The combination with the board clamps of a drop hammer of a head piece thereon, and a floating plate apertured for passage of the board and laterally supported against **20** movement with respect to the head piece upon each side of the board to prevent said plate from flying in case of breakage.

HOWARD TERHUNE.
